UNITED STATES PATENT OFFICE.

DIGBY WILLIAM CHANDLER, OF NEW YORK, N. Y., ASSIGNOR TO ANNIN & CO., OF NEW YORK, N. Y., A CORPORATION OF NEW YORK.

DESIGN FOR A DOLL.

Application filed February 23, 1926. Serial No. 16,643. Term of patent 7 years.

To all whom it may concern:

Be it known that I, DIGBY W. CHANDLER, a citizen of the United States, residing in the city of New York, borough of Manhattan, in the county and State of New York, have invented a new, original, and ornamental Design for Dolls, of which the following is a specification, reference being had to the accompanying drawings, forming part thereof.

I claim:

The ornamental design for a doll, as shown.

DIGBY WILLIAM CHANDLER.
